ADJUSTABLE LID SUPPORT

Charles Hammersley, Jeffersonville, Ind.

Application December 1, 1933, Serial No. 700,607

2 Claims. (Cl. 217—61)

The present invention relates to a support for the lids of cigar boxes and the like so as to display the contents of the box and the labels usually found on the inside of the lid to advantage.

The object of the invention is to provide a support of this nature which is simple in its construction, inexpensive to manufacture, easy to manipulate, handy to install and remove and otherwise well adapted to the purpose for which it is designed.

With the above and numerous other objects in view as will appear as the description proceeds, the invention consists in certain novel features of construction, and in the combination and arrangement of parts as will hereinafter be more fully described and claimed.

In the drawings:

Figure 1 represents a front elevation of an open box, a portion of the front wall being broken away and my support being mounted on the lid.

Figure 2 is a vertical transverse section therethrough.

Figure 3 is a vertical transverse section through the box showing the lid in closed position.

Figure 4 is a fragmentary rear elevation of the box showing the lid open with my support in place.

Figure 5 is a fragmentary rear elevation showing the lid closed.

Figure 6 is a perspective view of the support, and

Figure 7 is a detail rear elevation of the box showing the slit provided in the flexible hinge for accommodating my support.

Referring to the drawings in detail it will be seen that numeral 5 denotes an ordinary cigar box or the like and numeral 6 the ordinary lid therefor connected therewith by the usual cloth or flexible hinge structure 7. One end of this hinge structure is cut to provide a slit 8 as shown to advantage in Figure 7 as also indicated in Figure 5. My support is formed from a single sheet of metal to provide an elongated body 9 from the bottom end of which extends right angularly a portion 10 merging into an upstanding portion 11 parallel to the body 9 which in turn merges into an outwardly directed portion 12 bent under upon itself, and forming a handle. The upper end of the plate 9 has on one end thereof a right angle extension 14 merging into a right angle extension 15 disposed parallel

across the body 9. In installing the support the portion 10 is slid into slit 8 and the body 9 is on the outside of the lid and the portions 15 and 11 on the inside of the lid. When the lid is raised and the support is slid down to the position shown in Figure 2 the handle portion 12 will rest on the edge of the rear wall of the box and thus hold the lid in an upright rearwardly tilting position to display a label to best advantage. By lifting up on the handle portion 12 the lid may be easily closed as will be seen to advantage in Figure 3.

It is thought that the construction, operation, and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:

1. A device for supporting the lid of a box in raised position comprising an elongated strip of flat stock of considerable width having one end bent into U-shape to provide a long limb and a short limb, said limbs being straight and paralleling each other, the space between the limbs receiving the rear edge of a lid, with the long limb resting on the top of the lid and the short limb engaging a part of the underface of the lid, the extremity of the short limb being bent outwardly at right angles to provide a handle and a part for engaging the edge of the rear wall of the box when the lid is in raised position and the device moved rearwardly on the lid, said handle and the two limbs occupying a common vertical plane when the device is in horizontal position.

2. A device for supporting the lid of a box in raised position comprising an elongated strip having one end bent into U-shape to provide a long limb and a short limb, the extremity of the short limb being bent outwardly at right angles, the two limbs and the outwardly bent part occupying a common vertical plane when the device is in horizontal position and an angle-

shaped member at the free end of the long limb, said member providing a long part and a short part, the short part being connected to a side edge of the long limb and being of the same width as the width of the bight of the U-shaped part, the long part extending trans-

versely in spaced relation across the said free end of the long limb and said long part lying in the same horizontal plane as the short limb of the U-shaped part, when the device is in horizontal position.

CHARLES HAMMERSLEY.
